UNITED STATES PATENT OFFICE.

HUGO DICKE, OF FRANKFORT-ON-THE-MAIN, GERMANY, ASSIGNOR TO
JACOB EDUARD GOLDSCHMID, OF FRANKFORT-ON-THE-MAIN, GERMANY.

PROCESS OF MAKING GAS.

No. 839,459

Specification of Letters Patent.

Patented Dec. 25, 1906.

Application filed September 27, 1901. Serial No. 76,796.

To all whom it may concern:

Be it known that I, HUGO DICKE, head engineer, residing at Frankfort-on-the-Main, Neue Mainzerstrasse No. 14, in the German Empire, have invented new and useful Improvements in the Manufacture of Gas, of which the following is a specification.

My invention relates to the process of generating an illuminating-gas by carbonizing gas-coal in retorts in the usual way and passing water-gas through the retorts during the generation of the coal-gas.

My invention relates more particularly to the regulation of the current of water-gas, with the object of preventing, as much as possible, the decomposition of the heavy hydrocarbons and of introducing only such quantities of water-gas as will not diminish the candle-power of the resulting mixed gas below the allowable limits. For this purpose I begin to admit the water-gas immediately or soon after the beginning of the distillation, and I continue the operation until the mixture of heavy hydrocarbons and of light gases developed in the retort has attained a ratio which will prevent the decomposition of the heavy hydrocarbons by the heat of the retorts without further dilution by water-gas. I have further found it to be advantageous to admit more water-gas during the first part of the distillation and to diminish the quantity toward the end of it. In this way the amount of water-gas admitted amounts to from thirty per cent. to forty per cent. of the total amount of generated mixed gas.

I admit the water-gas during periods varying from about one hour and a half to three hours of the distillation period, and I regulate the admittance for different coals in accordance with the following rule: The ratio of the heavy hydrocarbons to the light gases is about one to nine from the end of the first quarter of an hour, one to fifteen at the end of the first hour, and one to twenty at the end of the second hour for ordinary coal, whereas Boghead coal yields about triple the amount of heavy gases. Now the ratio one to twenty is about the degree of dilution which will prevent the decomposition of the heavy hydrocarbons. The water-gas should therefore be regulated so that this dilution at least will be maintained during the whole process. It follows that it is best to admit

more water-gas at the beginning, calculating 55 the absolute quantity of coal-gas developed, as well as its ratio to the generated light gases.

In the case of ordinary coal, as above noted, the distilling operation in the retort 60 develops during the first quarter of an hour one part of heavy hydrocarbons to nine parts of light hydrocarbons. Assuming these proportions, for the sake of comparison, to be represented by one hundred cubic feet of 65 heavy hydrocarbons and nine hundred cubic feet of light hydrocarbons, my invention would contemplate the admission into the retort during the initial period referred to of eleven hundred cubic feet of water-gas as a 70 minimum. During the next three-quarters of an hour, as above noted, the distilling operation develops the same quantity of heavy hydrocarbons developed during the first quarter of an hour, but a larger quantity of 75 light hydrocarbons. Again assuming, for the sake of comparison, the proportions of heavy hydrocarbons and light hydrocarbons developed during this second period of gas generation (one to fifteen) to be represented 80 by one hundred cubic feet of heavy hydrocarbons and fifteen hundred cubic feet of light hydrocarbons, my invention would contemplate introducing during the second period referred to five hundred cubic feet of 85 water-gas. It is to be noted, however, that inasmuch as the second period is three times as long as the first the amount of water-gas necessary to be admitted is proportionately less for equal time intervals in the second 90 period than in the first, and a corresponding diminution is feasible during the next succeeding period of an entire hour, as will be readily understood. I have pointed out, however, that while the minimum admission 95 of water-gas indicated must be substantially maintained, it is, nevertheless, feasible to increase that proportion up to a maximum of from thirty to forty per cent. of the total amount of generated mixed gas, which is of 100 obvious importance from a practical standpoint.

Having thus described my invention, what I claim is—

The process of making gas which consists 105 in distilling coal in retorts, and diluting and protecting the heavy hydrocarbons incident to such distillation, by introducing into the

retorts an amount of water-gas, which, together with the amount of distilled light gases simultaneously present, shall bear the minimum ratio of twenty to one to said heavy hydrocarbons, whereby decomposition of said heavy hydrocarbons is prevented; substantially as described.

In testimony whereof I have signed my name to this specification in the presence of two subscribing witnesses.

HUGO DICKE.
